UNITED STATES PATENT OFFICE.

CHARLES G. BUCHANAN, OF EAST ORANGE, NEW JERSEY.

CRUSHER.

1,386,764.

Specification of Letters Patent. Patented Aug. 9, 1921.

Application filed November 11, 1920. Serial No. 423,246.

To all whom it may concern:

Be it known that I, CHARLES G. BUCHANAN, a citizen of the United States, residing at East Orange, in the county of Essex and 5 State of New Jersey, have invented certain new and useful Improvements in Crushers, of which the following is a specification.

This invention relates to crushers and particularly to the frames of rock and ore 10 crushers employing a swinging jaw driven for instance by a toggle. Such crushers are large in size so that their manufacture and transportation requires the frames to be cast in sections which are assembled at the 15 place of installation. The object of this invention is to provide a crusher frame in separable parts with the heads at each end between side frame members constructed to receive the crushing stresses from the heads 20 and hold the heads permanently in place against failure or loosening in service.

In the accompanying drawings illustrating the invention—

Figure 1 is a plan view of a crusher showing a sectional frame construction,

Fig. 2 is an elevation view of one portion of the crusher shown in Fig. 1, and,

Figs. 3 and 4 are plan views of modifications.

30 In the specific embodiment of the invention shown in Figs. 1 and 2 a shaft 4 with fly wheels 5 drives the toggles t_1 , t_2 through an eccentric to oscillate the swinging jaw J around its shaft S toward and from the 35 fixed jaw j. The crushing stresses are therefore longitudinal from front to back and are taken up by the rear head 6, and the front head 7 carrying the fixed jaw j. The crusher frame is sectional in formation and 40 the heads 6, 7, are set in between in the inner faces of the ends of the side frame members 8. The ends of the heads are provided with shoulders 9 projecting into grooves 10, 11 in the side frames which grooves extend 45 throughout the entire depth of the respective frames. The shoulders may be on the side frames instead of on the heads, this alternative construction being indicated in Fig. 3 by dotted lines 42.

50 Due to the repeated shocks to which these parts are subjected the metal where overstrained is particularly likely to show fatigue first weakening and then failing. In a corner, such as 12 for instance, there 55 are the direct tensile stresses due to the crushing action and induced torsional

stresses due to the yielding of the parts however slight, the extreme ends of the side frames tending to flex outward so that the joints 14 between the parts unless securely 60 held will tend to open. These combined stresses unless counteracted will produce a concentration of the strains in the corner which will have a tearing effect on the metal and by constant repetition of the crushing 65 shocks will finally fracture the side frames beyond repair.

In the structure of this invention the concentration of stresses and overstraining of the metal is prevented by interlocking and 70 stiffening the parts to effect a distribution of the crushing force and bring about a mutual supporting relation between the side frames and heads. In the embodiment of the invention shown in Figs. 1 and 2 the 75 meeting surfaces of heads and side frames are carried outward in extended contact along the lines 14, the ends of the side frames are in the form of boxes surrounding core spaces 19 by outer portions 20, cross 80 webs 21 and inner portions 22, which carry the grooves 10, 11. The side frames are drawn together against the ends of the head by transverse bolts 15 passing through the parts substantially in line with the shoulders 85 32. The extreme ends of the side frames continue as the vertical flanges 25 fitting against extended flanges 26 of the heads. Short bolts 27 grip the two flanges together and a series of horizontal webs 29, 90 30 on the sides and heads respectively stiffen and strengthen the flanges.

The parts are so machined that the meeting surfaces of the flanges are pressed 95 tightly together at 14 with the shoulder, 9, slightly clearing the bottoms of grooves 10, 11 and the corners 12, 12' are preferably filleted on a radius of about one quarter of an inch. The bolts 27 are positioned at a distance from the stress receiving shoulder 100 32 of the rib and groove so as to have a relatively large leverage in holding the parts from flexing apart. The large contacting surfaces of flanges 25, 26 distribute the torsional stresses without concentration and the 105 stiffened extended ends aid in maintaining a rigid fixed engagement between the parts without appreciable flexure. With these parts thus held against yielding the crushing force has no opportunity to concentrate 110 its stresses at any single point such as corner 12 but is evenly distributed as compressive

efforts along shoulder 32. All strains are kept safely within the elastic limit of the metal and fatigue of the latter does not occur.

- 5 In the modification shown in Fig. 3 the short bolts 27 are replaced by long bolts 37 extending across the ends from one side frame to the other, the ends of the side frames being extended as at 38 to overhang 10 the heads. In such a construction the flanges 26 of the heads may be dispensed with and the bolts 37 will be drawn tight to firmly resist any outward flexure of the frame ends thus maintaining the surfaces at shoulder 32 15 in even extended contact without undue concentration at any point, but the preferred construction retains the brackets and ribs on the heads as shown by dotted lines 40—41 Fig. 3; for the reason that this construction gives increased bearing of surfaces 20 in contact between the members, that is the front and rear heads and side frames. In Fig. 4 the head 47 is carried out and 25 around the ends 48, 49 of the side frames and is slotted as at 50, 51 to tightly fit these extended ends 48, 49. Bolts 52 are passed through the overhanging flanges 53, 54 of the head and through the extensions 48, 49 of the side frames and drawn tight to bind 30 the parts firmly together. In such a construction there is no opportunity for any

outward flexure of the ends of the side frames as the flanges 53, 54 with the bolt 52 hold these ends 48, 49 firmly against the body of the head 47.

35

I claim:—

1. In a crusher the combination with a frame having sides with inward directed ends and transverse thrust bearing shoulders thereon, of a separable head set against said shoulders, and means for drawing said sides against said head and for resisting flexure of said sides by the outward pressure of said frame comprising flanges extended longitudinally from the ends of said frame 45 sides and bolting means drawing inwardly on said flanges and spaced from said shoulders.

2. In a crusher the combination with a frame having sides with inward directed 50 ends and transverse thrust bearing shoulders thereon, of a separable head set against said shoulders, transverse bolts for drawing said sides against said head substantially in line with said shoulders, and means for resisting flexure of said sides by the outward pressure of said frame comprising flanges extended longitudinally from the ends of 55 said frame sides and bolts extending between said flanges and drawing inwardly thereon. 60

CHARLES G. BUCHANAN.
